UNITED STATES PATENT OFFICE.

WILLIAM T. BRADLEY, OF ROCHESTER, NEW YORK, ASSIGNOR OF ONE-HALF TO LOUIS P. WILLSEA, OF SAME PLACE.

CLOTHES-WRINGER.

SPECIFICATION forming part of Letters Patent No. 640,440, dated January 2, 1900.

Application filed October 3, 1898. Serial No. 692,497. (No model.)

To all whom it may concern:

Be it known that I, WILLIAM T. BRADLEY, of Rochester, in the county of Monroe and State of New York, have invented certain new and useful Improvements in Clothes-Wringers; and I do hereby declare the following to be a full, clear, and exact description of the same, reference being had to the accompanying drawings, forming a part of this specification, and to the reference-numerals marked thereon.

My present invention relates to clothes-wringers, particularly of that class in which the rollers are maintained in contact by spring action when in operation and are relieved of the action of the springs when not in use, and has for its objects to improve, simplify, and cheapen the construction and provide for the ready adjustment of the tension or pressure springs; and to these and other ends it consists in certain improvements in construction and combinations of parts, all as will be hereinafter described, and the novel features pointed out particularly in the claims at the end of this specification.

In the drawings, Figure 1 is a perspective view of a wringer embodying my improvements with one of the cover-plates for the operating parts removed; Fig. 2, a longitudinal sectional view of the same; Fig. 3, a cross-sectional view on the line $x-x$ of Fig. 2. Fig. 4 is a perspective view of the bearings for the rollers detached from the frame.

Similar reference-numerals indicate similar parts.

The main frame of the wringer embodies the vertical standards 1, preferably constructed of cast or sheet metal and connected at the top by a cross-plate 2, having the flanges 3 at the ends extending over the ends of the standards, and at the lower portion by a tie-rod 3. The standards are hollow to contain the bearings and tension devices for the rollers, which are covered by plates 4, as shown in Fig. 2, and the front and rear of the lower ends of said standards are arranged to contact with a tub or support and to be held firmly in position by means of swinging clamp-arms 5, pivoted at 6 to lugs 7 on the inner faces of the standards and adapted to swing to either side thereof, suitable clamping

screws 8 being located on the clamp-arms, as shown. By this means the wringer may be applied to either side of a tub or other support and firmly held in position thereon, and in order that the clothes may be guided and supported properly toward the rollers 9 and 10 and also that the expressed water may be properly directed I provide a reversible deflecting-plate 11, preferably substantially inverted-V shaped, as shown, adapted to be placed on either side of the machine and to coöperate with lugs or flanges 12, formed on the inner sides of the standards and to be held and supported thereby, said plate when in use resting upon one lug and extending beneath the other, as shown particularly in Fig. 3. The standards are further provided on their inner faces with the clothes-guard flanges 13 at the sides in line with the meeting surfaces of the rollers, and also with the vertical guiding-flanges 14, forming ways for the bearings of the rollers. The rollers are provided with the usual elastic covering, and the arbors thereof extend into the standards through the slots therein and operate in suitable half bearing-blocks 15, preferably of wood, those for the lower roller (to which roller the operating-handle is connected, as usual) being contained in open-sided removable metal boxes 16, supported in the lower ends of the slots in the standards.

The sliding boxes 17 for the bearing-blocks 15 of the roller 9 are guided on the flanges 14 at the sides of the slots in the standard and are provided with the depending yokes 18, preferably formed integral therewith, extending below the lower bearings and connected with the hooks at the upper ends of coil-springs 19, arranged in the standards and having their lower ends provided with the loop or hook extending around eccentric cams 20, formed on levers 21, pivoted at 22 in the standards, and having their outer operating ends extending out through slots in the cover-plates. The cams are preferably arranged on the levers so that when the levers are moved down to the position shown in dotted lines in Fig. 2 the springs are not under tension, but when moved to the position shown in full lines the springs will be put under tension and the rollers drawn in contact and

held, the higher portion of the cam being then outside of the pivotal centers, so that the levers will be drawn by the springs against the cover-plates.

5. I prefer to make the spring-adjusting levers with the eccentric cams thereon, as their movement is thereby rendered more easy; but the principal feature is the eccentric connection of the spring and lever, whereby when 10 the latter is turned to one position the spring tension is given the rollers, and when moved to the other the springs are loose and the rollers are not pressed together.

The wringer thus constructed is very simple and cheap in construction, and the springs being extensible instead of compressible are much less liable to break and can be very readily attached when assembling the parts.

I claim as my invention—

20. 1. The combination with the main frame having the standards, the rollers, and spring-operating devices for the latter, of the reversible clamps on the standard, and the reversible inverted-V-shaped plate, and engaging 25 lugs on the standards with which it co-operates.

2. In a wringer, the combination with the hollow slotted standards and the rollers, of the stationary bearings, the movable bearings having the depending yokes within the standards and extending beyond the stationary bearings and sliding in the standards, the springs located within the standards and engaging the lower ends of the yokes, and adjusting devices connected to the springs for 35 adjusting them.

3. In a wringer, the combination with the hollow slotted standards having the ribs 14,

the stationary bearing-boxes 16, and the movable bearing-boxes 17 having the depending 40 yokes guided on the ribs 14, of the tension-springs connected to the yokes, means for adjusting the springs, the cover-plates 4 and the rollers.

4. The combination with the main frame 45 having the hollow slotted standards provided with the ribs 13 and 14 and the cover-plates 4, of the rollers, the boxes 16 and 17, the latter having the yokes 18, the springs located within the standards, and means for adjusting 50 them.

5. In a wringer, the combination with the main frame having the slotted hollow standards, and the rollers, of the removable open-sided bearing-boxes for the lower roller arranged in the slots, the wooden bearing-blocks therein, the movable bearing-boxes also sliding in the slots in the standards, having the yokes extending beyond the bearings of the other roller, the springs engaging the 60 yokes, and means for adjusting the tension of the spring.

6. In a wringer, the combination with the main frame, and a stationary and a movable roller, of the movable bearings for the movable roller having the yokes, the tension-springs connected to the yokes, and the levers pivoted in the frame having the eccentric cams engaging the free ends of the springs and adapted to be moved across the center to 70 lock the springs under tension.

WILLIAM T. BRADLEY.
